To all whom it may concern:

Be it known that I, Adolph J. Nelson, a citizen
of the United States of America and a resident
of Oak Park, in the county of Cook and State of
Illinois, have invented a new, original, and or-
namental Design for a Clock, of which the follow-
ing is a specification, reference being had to the
accompanying drawing, forming a part thereof,
and in which:

Fig. 1 is a front elevation view of a clock, show-
ing my new design; and

Fig. 2 is a side elevation view thereof.

I claim:

The ornamental design for a clock, as shown.

ADOLPH J. NELSON,
